E. P. H. CAPRON, OF SPRINGFIELD, OHIO, ASSIGNOR TO HIMSELF, GEORGE H. GERRISH, AND D. B. RICH.

Letters Patent No. 76,888, dated April 21, 1868.

IMPROVED BRICK-MACHINE.

The Schedule referred to in these Letters Patent and making part of the same.

TO ALL WHOM IT MAY CONCERN:

Be it known that I, E. P. H. CAPRON, of Springfield, in the county of Clark, and State of Ohio, have invented new and useful Improvements in Brick-Machines; and I do hereby declare the following to be a full and correct description of the same, sufficient to enable others skilled in the art to which my improvements appertain to fully understand and construct the same, reference being had to the accompanying drawings, which make part of this specification, and in which—

Figure 1 is a vertical section of my improved brick-machine in line xx , fig. 2

Figure 2 is a top view of the same.

Figure 3 is a partial and sectional side elevation of the same.

Figure 4 is a sectional side view, and

Figure 5 a sectional end view of my improved follower.

Like letters indicate like parts in the several figures.

My improvements belong to that class of brick-machines in which a revolving table contains the moulds, which, as they pass under the cylinder, are filled, and from which the bricks are pushed out by followers, when the moulds have passed under the cylinder; and my improvements consist in providing the surface of the revolving table, between the moulds, with steel plates, for purposes hereinafter described.

Also, in the peculiar construction of the screw-blades in the cylinder, which force the clay into the moulds, and the manner of attachment to the main shaft.

Further, in novel means of securing and operating the striker-plate, and of giving a pressure from below to the brick when under the striker-plate, so as to insure a uniform density of the brick; and

Lastly, in the construction of the follower, the means of supporting it, and adjusting its upper plate, and attaching to the latter the covering of cloth commonly used.

In the drawings, A may represent the bottom pieces of the frame, connected by cross-beams, B, in one of which the main shaft, C, has its lower bearings. This shaft passes through the stationary circular plate D, and supports the revolving table E, the pivot of which it forms, and which is provided with moulds a . The shaft C passes through its upper bearing in a beam, F, supported from the cross-beam, which connects the upright beams G, and is on its top provided with a gear-wheel, H, which meshes with another smaller gear-wheel, I, on the shaft J, which has its upper bearing on the upper cross-beam, its lower one being formed by a shoulder on the shaft J, resting on a cross-piece, K, about the centre of the cylinder L, just above the screw-blades M, the shaft passing through the piece K into the screw-blades. These latter are cast solid, with an opening in the centre large and deep enough only, however, to allow the lower end of the shaft J to pass into the same sufficiently to allow their being securely attached to the shaft by means of a set-screw, b. As now constructed, these screw-blades have the opening pass entirely through their centre, the shaft passing entirely through the same, and causing the blades to frequently split at the lower part of the opening, which is entirely obviated by my improved mode of fastening the blades to the shaft. The opening in the bottom of the cylinder is of a width corresponding to the length of the moulds a in the revolving table E, and each of the screw-blades M has a part or shoulder, c, of sufficient size to allow them to freely revolve in the opening in the bottom of the cylinder L. These shoulders c are a continuation of the lower curve of the blades, and diverge in opposite directions from the centre of the blades.

The cylinder L is secured on a platform or table, N, which is supported by the beams G and standards d, as shown in figs. 1 and 2.

The moulds a in the revolving table E are of the usual construction, but the interval or space between each two moulds I cover with steel plates, e. Revolving mould-tables are now commonly cast, and the continual rubbing of the clay on their surface very soon wears them out, and makes them uneven, especially at the long edges of the moulds, which results in the brick being made with uneven edges, and of an uneven appearance.

I prevent this difficulty by letting the steel plates *e* in between the moulds *a*, as described, the edges and surface of which will be polished by the friction, and then prevent the adherence of clay to the surface of the revolving table, and consequent resistance or friction.

These steel plates *e* will be so fitted and secured to the face of the mould-wheel, that they can be readily detached when worn by use, and others substituted in their place. By this means the necessity of making a new mould-wheel at short intervals is entirely obviated, and this is of special importance where the machines are to be used in country places or small villages, where large foundries and machine-shops do not exist, as in such cases the machine can be supplied in the first instance with any desired number of extra plates, which can be inserted whenever required, without taking the machine apart, or stopping its use but for a few moments.

In figs. 2 and 3 my improvements in the striker-plate are clearly shown. *f* is a short plate, cast with and on the cylinder *L*, a sufficient distance above the revolving mould-table *E* to allow the striker-plate *g* to freely slide under it. Near the cylinder, and about the middle of this plate *f*, is a hole, through which a rod, *h*, passes, and rests against the surface of the striker-plate, *g*. The upper end of this rod is provided with a screw-thread, *g*¹, which passes through a lug, *g*², on the upper cross-beam, and is made adjustable by a nut, *i*. By adjusting the rod *h* by means of the nut, it can be made to press more or less on the striker-plate *g*, according to the pressure the same is desired to exert on the clay in the moulds. At its outer end the plate *g* has a short post, *i*¹, provided with a horizontal hole, through which a rod, *i*², passes, the rod being pivoted on the plate *g* at *i*³. It will be seen that the striker-plate *g* is thus held merely by the friction of the rod *i*² in the post *i*¹, which is regulated by a set-screw, *j*, and by the friction of the rod *h* on its surface.

The rod *h* adjusts the pressure the plate *g* exerts on the bricks in the moulds, and the rod *i*² keeps the plate in place. Should any stones or stems get into any of the moulds, which cannot pass under the striker-plate, and threaten to do damage to the machine, the friction of the rod *i*² in the post *i*¹ is not so powerful as to prevent the striker-plate from slipping from its place, which at once indicates to the attendant that the mould over which it lies must be cleared. The amount of friction is adjusted by the set-screw *j*.

As the striker-plate exerts its pressure upon the top of the bricks, it often happens that the lower part of the same is less dense or compact than the top, thus making a weak and uneven brick. I overcome this defect by another improvement on brick-machines.

The stationary plate, *D*, bears the usual circular cam, *O*, by means of which the followers are enabled to discharge the bricks from the moulds. I form a horizontal slot, *k*, in the straight part of the cam, just under the striker-plate. In this slot, by means of a set-screw and nut, *k*', I secure a plate, *l*, having an inclined upper edge, and provided with a vertical slot, *l*'. As the followers bring the bricks under the striker-plate, its roller ascends the inclined plate *l*, and thus an equal pressure is exerted on the brick from all sides, and its evenness of density is certain. The plate *l* is adjustable by means of the slots *k* and *l*', both vertically and laterally, and thus controls the amount of pressure exerted through the follower.

Figs. 4 and 5 are detached views of the follower, which consists of the main T-shaped part *m*, the end-pieces *n*, and the top-plate *a'*. A peculiarity of my follower is that its roller does not, as in other brick-machines, rest on the cam *O* during the entire revolution of the revolving table *E*, but comes in contact with the same only on its inclined part, *o'*, as shown in figs. 1 and 3. I support my followers by means of rods *p*, pivoted in recesses *n'* in the middle of the end-pieces *n*. These rods are kept in an outwardly-projecting position by means of the spring *q*, one end of which is fastened in the recess *n'*, whilst the other bears against the rods *p*. The moulds, at the lower part of their inner sides, are provided with inclined slots *r'*, forming at their lower end a shoulder, *r*. Against these shoulders *r* the ends of the rods *p* rest when supporting the follower, but when the incline *o'* elevates the follower, the converging sides of the slots *r'* force the rods *p* against the springs *q* into the recesses *n'*. When having passed the incline, however, the follower again sinks down in the mould, the springs *q* forcing out the rods *p* from the recesses *n'* as the sides of the slots *r'* diverge, and cause the lower ends of the rods to rest against the shoulders *r*.

The wear and tear of the follower rollers in common machines on the inclined cam causes the bricks to become uneven, one follower-roller, or one place on the inclined cam, wearing away more than another. It will be easily understood that by my mode of supporting the follower, this difficulty is entirely overcome.

The length of the rods *p* will of course determine the thickness of the bricks. To enable me to change the size, and to compensate for any wear and tear of the parts, I make the lower ends of the rods *p* adjustable, by providing therewith a screw-thread and a screw-cap, *s*, the operation of which will be easily understood. In fig. 5 the rod *p* on the left side of the follower is shown in position when the latter is on the incline *o'*, and the right one in position when the follower is just about to pass under the cylinder *L*.

In machines in which the top-plate of the follower is made adjustable, and covered with cloth, the cloth is usually sewed on to the plate, perforations being provided for the thread. Great inconvenience, however, is experienced in this mode of fastening, as the threads on the under side of the plate break continually, which is caused by the friction of the same between the two metal surfaces. I cast this plate with a recess, *t*, around and across its under side, and with suitable perforations passing through the same. Into these recesses I place strips of leather, and through and over this I make the stitches. The leather being a soft material, no danger arises of breaking the thread, and it is dense enough to secure the cloth to be held firmly. In fig. 4, a sectional side view clearly shows this improvement.

I am aware that the top-plate of the follower has before been made adjustable on its front side, the rear part being hinged to the follower for the purpose of compensating for the greater compactness of the brick on the rear side. But it is not always on the rear side that the brick is made denser, as circumstances, such as the position of the pressing and filling-screw blades, often bring the greatest density to the centre of the brick. To

enable me to adjust either side, as circumstances may require, I make the top-plate of the follower entirely detached from the same, with its edges bevelled as shown, and secure it to the follower by means of screws, *u*, as shown in fig. 4, and to adjust it, use set-screws, *v*, placed on the outer edges of the plate. Thus, if I desire to adjust either side of the plate, I elevate or lower it, by means of the screws *v*, and then securely hold it by means of the screws *u*.

I have also an improved mode of securing and adjusting the roller *w* of the follower, by pivoting it in a box, *w*¹, which slides in a recess, *w*², in the under side of the main part, *m*, and holding it by set-screws, *y*, while their position in the recess *w*² is adjusted by set-screws *z*, against which the box bears.

By all these means of adjustment, I am enabled to fix the moulds to a nicety, to produce any-sized brick, being at the same time certain that it will come out even and compact in every part.

Having thus described my invention, what I claim is—

1. Securing the striker-plate in position, by means of the rod *i* and set-screw *j*, arranged to operate substantially as described.
2. The rod *h*, provided with a nut, *i*, and arranged to bear upon the striker-plate *g*, substantially as set forth.
3. I claim facing the iron mould-wheel *E*, above described, with the detachable V-shaped steel plates *e*, substantially as set forth.
4. The incline *l*, made adjustable both horizontally and vertically, for varying the pressure and pressing the brick from below, substantially as described.
5. Providing the follower *m* with the hinged supports *p* thereon, and the springs *q*, for supporting the follower clear from the track while the moulds are passing under the hopper, substantially as described.
6. The combination and arrangement of the hinged supports *p*, nuts *s*, and the shoulders *r'* in the mould-wheel, for adjusting the follower to vary the thickness of the brick as desired.
7. Providing the follower *m* with a friction-roller, *w*, that can be adjusted to compensate for the wear of the rollers, or the track, or both, substantially as set forth.
8. Securing the cloth to the plate by means of the grooves *t*, and leather strips placed therein, and sewing through the leather, substantially as described.
9. The plate *a'*, with bevelled edges, and adjusted on the follower *m* by means of the screws, substantially as set forth.

E. P. H. CAPRON.
